(57) **CLAIM**

The ornamental design for a hand grip exerciser, as shown and described.

DESCRIPTION

FIG. 1 is an upper right front perspective view of a hand grip exerciser, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the hand grip exerciser in which the design is embodied that are not considered part of the claimed design.
